UNITED STATES PATENT OFFICE.

ERNEST O. MESSMORE, OF TIPTON, INDIANA.

ODORLESS GARBAGE-RECEPACLE.

1,156,304.

Specification of Letters Patent. Patented Oct. 12, 1915.

Application filed October 13, 1914. Serial No. 866,500.

To all whom it may concern:

Be it known that I, ERNEST O. MESSMORE, a citizen of the United States, residing at Tipton, in the county of Tipton, State of Indiana, have invented certain new and useful Improvements in Odorless Garbage-Receptacles; and I do hereby declare the following to be a full, clear, and exact description of the invention, such as will enable others skilled in the art to which it appertains to make and use the same.

This invention relates to improvements in garbage receptacles, and particularly to garbage receptacles which are adapted to prevent odors escaping therefrom.

One object of the invention is to provide a garbage receptacle which is simple in operation and construction and which will effectually prevent escape of odors from the interior of the receptacle when the cover is raised.

Another object is to provide a garbage receptacle of such construction that the same can be readily taken apart and cleaned.

Other objects and advantages will be apparent from the following description when taken in connection with the accompanying drawings.

In the drawings: Figure 1 is a side elevation of a garbage can made in accordance with my invention. Fig. 2 is a front elevation. Fig. 3 is a top plan view. Fig. 4 is a sectional view on the line 4—4 of Fig. 3. Fig. 5 is a transverse sectional view on the line 5—5 of Fig. 4, and Fig. 6 is an enlarged sectional detail view of a portion of the rotary member within the upper portion of the receptacle.

Referring particularly to the accompanying drawings, 10 represents a cylindrical member which is open at both top and bottom, a removable bottom 11 being secured to the bottom of the cylinder and disposed against a suitable packing washer 13. The periphery of the bottom is provided with a plurality of radially extending ears 13 in which are pivotally carried the bolts 14, these bolts being arranged to engage between the bifurcated portions of the angle plates 15 secured to the sides of the cylinders above the ears. The upper ends of the bolts carry nuts 16 for drawing the bottom firmly into clamping relation with the cylinder. Disposed on the upper end of the cylinder is a plate 17 also provided with the

peripheral ears 18, but these ears are bifurcated as shown, and receive therein the upper ends of the clamping bolts 19 pivotally carried by the brackets 20 mounted on the cylinder below the ears. Mounted on this plate 17 is a casing 21 which is disposed over an opening 22 formed in the plate 17 which leads into the interior of the cylinder 10 or body of the receptacle. Disposed transversely in the casing and journaled in the sides thereof is a shaft 23 the intermediate portion of which is squared in cross section as shown at 24. Secured to each of the faces of the squared portion 24 is the intermediate portion of an integrally connected pair of wings 25 over which is secured a similar pair of wings 26. Suitably secured between the outer ends of the wings are rubber strips 27 while between the side or marginal edges are secured similar strips 28. The strips 27 bear firmly against the curved wall of the casing 21 while the strips 28 bear firmly against the vertical opposite side walls of the casing. It will be noted that the outer ends of the strips 27 and 28 are cut away at their adjacent points so that when the said strips bear against the walls of the casing they will be bent downward resulting in the said ends of the strips coming close together. From one end of the opening 22 is a curved plate 29 which is of the same width as the casing 21 and against which the strips 27 successively bear. This plate extends above and below the top 17, a short curved wall 29' extending from the upper end of the wall 29 to the adjacent wall of the casing. The structure just described forms a rimless wheel in which there are four radiating blades adapted to be brought successively in a horizontal plane below the opening 30 in the upper rectangular portion 31 of the casing. A hinged cover 32 is arranged to close this opening. On one of the outer ends of the shaft 23 is secured a ratchet wheel 33, and on this shaft but loosely rotatable thereon is a hand lever 34 which carries a spring pressed pawl 35 disposed for engagement with the teeth of the wheel 33.

In the operation of the device the cover 32 is raised and the garbage deposited through the opening 30, the same falling onto one of the blades of the wheel. The cover is then closed, the lever 34 raised until the pawl 35 engages the next notch after which the lever is depressed so as to rotate

the shaft 23. This rotation of the shaft moves the blade which carries the garbage downwardly so that the garbage is dumped into the receptacle, and another blade disposed under the opening 30 in position for the next deposit. When the lower of the blades moves up into the portion of the casing opposite to that provided with the opening 30 it carries some odors with it, and to permit of these odors escaping there is formed an opening 36 in the side wall of the casing near the upper end.

The packing strips carried by the blades of the wheel effectually prevent the escape of any odors through the opening 30, even though the lid 32 should be left open, and furthermore, odors cannot continuously escape through the opening 36 as a blade is disposed at a point diametrically opposite to the first one. The upper plate 17 is suitably packed where it joins with the upper end of the body of the receptacle. By reason of the removable end of the top and bottom members of the receptacle it will readily be seen that when these are taken apart, the receptacle can be readily cleaned or may be used for convenience in dumping. Ordinarily the top would be taken off and the contents of the receptacle dumped through the upper end. Should the can be lifted over a point at which it is desired to deposit the receptacle, the bottom can be removed to

permit the contents to readily flow therefrom.

It will be noted that the blade, which is in position to receive the garbage, has its free end engaged at a point where the plate 29 joins the wall 29'. It will also be noted that the next succeeding blade remains in engagement with the lower end of the plate 29 until the first blade has engaged the upper end of said plate, thereby preventing odors getting past the blades at that side.

What is claimed is:

A garbage receptacle comprising a body, 45 a casing mounted on the body, said casing having an access opening, a rotary element within the casing, a plurality of radially extending blades carried by the rotary element, flexible packing members carried by 50 the ends and sides of the blades and bearing against the walls of the casing, and means carried by the rotary element for turning the said element in step by step fashion to bring each of the blades successively beneath the access opening and into position to discharge its contents into the receptacle.

In testimony whereof I affix my signature, in the presence of two witnesses.

ERNEST O. MESSMORE.
